UNITED STATES PATENT OFFICE,

ARCHIE L. DORSEY, OF RUSSELL TOWNSHIP, PUTNAM COUNTY, INDIANA.

VALVE-GEAR FOR ENGINES.

No. 856,851.

Specification of Letters Patent.

Patented June 11, 1907.

Application filed May 6, 1906. Serial No. 315,409.

To all whom it may concern:

Be it known that I, ARCHIE L. DORSEY, a citizen of the United States, residing in Russell township, in the county of Putnam and State of Indiana, have invented new and useful Improvements in Valve-Gears for Engines; and I do declare the following to be a full, clear, and exact description of the invention, reference being had to the accompanying drawings, and to the letters and figures of reference marken thereon, which form a part of this specification.

This invention relates to reversible engines, particularly to steam engines, whether stationary, portable, or locomotive, and the invention has reference especially to valve gearing thereof.

Objects of the invention are to provide improved reversing valve gearing for engines, so constructed as to permit operating engineers to readily readjust the parts thereof when lost motion results from wear in use, in order to maintain correct motions of the main valve or valves that control the admission of steam to the engine-cylinder or cylinders, a further object being to provide an improved support for shifting links and improved connections therefor that may be readjusted by unskilled attendants, without requiring shop tools or loss of time in sending such parts to shops for repairs or renewals, all to the end that durability and economy in ultimate results may be attained in a high degree.

With the above-mentioned and minor objects in view, the invention consists in an engine provided with a novel form of shifting link and hanger therefor, and in novel mechanism for moving and controlling the hanger; and, the invention consists further in the novel parts and the combinations and arrangements of parts, as hereinafter particularly described and claimed.

Referring to the drawings, Figure 1 is a side elevation of the main portion of a stationary engine having the invention applied thereto, parts of the engine being shown in section (approximately on the plane of the line A—A in Fig. 2); Fig. 2, a top plan of the engine and invention thereon; Fig. 3, a fragmentary side elevation of the shifting link and its hanger and an eccentric rod having a novel form of connection with the link; Fig. 4, a side elevation of the link and its support and connections; Fig. 5, an end elevation of the link and its support and connections; Fig. 6, a horizontal sectional view of the link

and its supporting devices (taken as on the line B—B in Fig. 7); Fig. 7, a vertical sectional view of the supporting devices of the link, as on the plane of the line C—C in Fig. 6; Fig. 8, a vertical sectional view of the intermediate supporting devices of the link on the line D—D in Fig. 7; and, Fig. 9, a fragmentary vertical sectional view as on the plane of the line E—E in Fig. 6.

In order to conveniently describe the invention, a simple type of stationary engine is shown in the drawings for the purpose, and it will be understood that the invention is equally applicable to other types of engines.

In the drawings, *a* designates the main frame or bed of the engine; *b*, the main shaft; *c*, the balance wheel or belt wheel on the shaft; *d*, the steam-cylinder; *e*, the valve-chest; *f* the valve-stem supported in a guide; *g* and *h* the eccentrics; *i* and *j* the eccentric-straps; and *k* and *l*, the eccentric-rods, of the engine, all being of suitable well-known construction except as hereinafter specified.

In practically carrying out the invention a standard *F* having a slot *m* is provided and suitably adapted to fit a part of the engine frame, or in some cases it may be attached to the boiler of a portable or locomotive engine where the boiler may be used as part of the engine frame. The standard serves as a guide and support for the link mechanism and is designed to be reversible to either right hand or left hand use. In the present case the standard is attached to the engine frame between the main shaft and the valve-chest, and a link-bearer *G* is supported and guided by a crosshead *G'* that is mounted so as to be adjusted vertically and guided in the standard which is provided with an adjustable bearing piece or slip *H* having adjusting screws *n*, and adjustable guides *I* and *I'* that engage the crosshead *G'*, other parts of the standard being adapted to guide opposite sides of the crosshead, and it will thus be seen that lost motion between the crosshead and its guides may be readily eliminated. A suitable wrist-pin *p* is attached to the crosshead *G'* and extends through the slot *m* of the standard. A link-holder *J* is formed as a sliding guide-bar and is mounted movably in the link-bearer *G* which is provided with an adjustable cap *K* on its top, and an adjustable bearing piece or slip *L* in a side thereof provided with adjusting screws *q*, so that the link-holder may be kept free of lost

motion in its guiding supporter, being in contact with the cap and the bearing piece. The link-holder J has a pair of arms M and M' that project horizontally and are formed as 5 journal bearings and provided with bearing caps r.

A shifting link N is provided with a boss s in which a pivot t is secured that extends through the boss so as to form a pair of trunnions at opposite sides of the link, the boss being attached to the middle portion of one main part of the link at one side of the link slot, and the pivot is mounted rotatively in the arms M and M', so that the link pivot 15 may move in a plane toward or from the valve-chest, being arranged between the valve-chest and the link-bearer G. The link has two wrist-pins u and v secured thereto, and the eccentric rod k extends above the 20 link-bearers and is adjustably connected to the wrist-pin u, while the eccentric rod l extends under the link-bearer and is adjustably connected to the wrist-pin v, the eccentric rods having adjustable caps w in engagement 25 with the wrist-pins for taking up lost motion. The link N has a movable block or die O mounted in its slot and connected to the valve stem f by means of a pivot pin x.

The mechanism for shifting the link N with 30 respect to the valve stem comprises a pivot y that is secured to the standard F, a tumbler P that is formed as a triangle and journaled at one of its corners on the pivot y and provided with an adjustable bearing cap 11 that engages the pivot. At another corner of the tumbler a wrist-pin 12 is secured thereto to which a lifting link Q is connected adjustably, being provided with an adjustable bearing cap 13 that engages the wrist-pin, 35 and the link Q is connected adjustably to the wrist-pin p of the crosshead G' to control and shift the crosshead, the link Q having an adjustable bearing cap 14 in engagement with the wrist-pin p. The remaining corner of 40 the triangular tumbler is provided with a wrist-pin 15 that is secured thereto, and a reach-rod R having an adjustable bearing cap 16 is connected to the wrist-pin 15 and also to a reverse-lever S that is suitably supported and in operative connection with a 45 quadrant T which also is suitably supported so as to hold the reverse-lever, the latter having a suitable latch engaging the quadrant.

It will be understood from the foregoing 55 that the link-holder may be withdrawn from one side of the link-bearer and inserted into the opposite side thereof, so as to be adjusted to conditions in case it be desired to reverse the position of the standard or 60 mount it on the opposite side of the engine. It should be understood also that in some cases a rock-shaft and arms may be interposed between the link block and the valve-stem. Also in case of reversal of the standard, the reach-rod may be turned over so as

to extend from the tumbler in the direction opposite to that shown.

In practical use, the reverse lever is to be operated in the usual manner and move the tumbler which in turn may either raise or 70 lower the link so as to shift the positions of the eccentric rods with respect to the valve stem, as will be understood, and during operation of the engine the shifting link-holder will slide in a horizontal plane and carry the link 75 while being moved by the link, the latter being moved by the eccentrics to operate the valve-stem and consequently the steam valve of the engine. When lost motion occurs at any of the bearings, compensation may be 80 quickly made by means of the adjustable parts of the bearings, but the link-holder being so designed as to permit of very large bearing surfaces, will not require frequent re-adjustments, nor will the pivotal supports 85 of the link, being arranged at both sides of the link, which construction prevents the link from wearing its bearings unevenly.

Having thus described the invention, what is claimed as new is—

1. A valve-gear including a stationary standard having a guide, a crosshead mounted on the guide, a link-bearer attached to the crosshead and provided with an adjustable cap on its top and also an adjustable bearing 95 slip in a side thereof, a link-holder mounted in the link-bearer and having a pair of arms provided with bearings and bearing caps, and a shifting link pivoted in the bearings.

2. An engine including a standard having a slot therein and provided also with guides, a crosshead mounted adjustably in the guides and having a wrist-pin attached thereto and extending through the slot of the standard, a movable tumbler mounted on the standard, 105 a link connected to the wrist-pin and also to the tumbler, means for operating and controlling the tumbler, a link-bearer attached to the crosshead, a shifting link provided with a link-holder mounted movably on the link-bearer, eccentrics having rods connected to the shifting link, a link block movable in the shifting link, and a valve-stem connected with the link block.

3. An engine including a standard having 115 adjustable guides, a crosshead mounted adjustably in the guides, means for adjusting and holding the crosshead in the guides, a link-bearer fixed to the crosshead, a link-holder mounted movably on the link-bearer 120 and having a pair of arms provided with journal-bearings, a shifting link having a link block and pivotally supported by the journal-bearings, eccentrics having rods connected to the shifting link, and a valve-stem connected with the link block.

4. An engine including a standard having guides, a crosshead mounted adjustably in the guides, means for adjusting and holding the crosshead in the guides, a link-bearer 130

- fixed to the crosshead and provided with an adjustable bearing-cap and also with an adjustable bearing-piece, a link-holder mounted slidingly in the link-bearer and engaged by 5 the bearing cap and the bearing-piece, a shifting link having a link-block and pivoted to the link-holder, eccentrics having rods connected to the shifting link, and a valve-stem connected with the link-block.
- 10 5. An engine including a stationary standard having guides, a crosshead mounted adjustably in the guides, means for adjusting and holding the crosshead in the guides, a link-bearer attached to the crosshead, a link- 15 holder mounted movably on the link-bearer and having a bearing provided with an adjustable cap, a shifting link having a link-block and pivoted in the bearing of the link-holder, eccentrics having rods connected to 20 the shifting link, and a valve-stem having operative connection with the link-block.
6. An engine including a stationary standard having guides, a crosshead mounted adjustably in the guides, means for adjusting 25 and holding the crosshead in the guides, a link-bearer attached to the crosshead, a link-holder mounted movably in the link-bearer, a shifting link pivoted to the link-holder and provided with fixed wrist-pins, a link- 30 block having sliding connection with the shifting link, a pair of eccentrics, straps on the eccentrics, rods attached to the straps
- and having bearings in connection with the wrist-pins and provided with adjustable caps also in connection with the wrist-pins, and a 35 valve-stem having operative connection with the link-block.
7. An engine including a stationary standard having guides and also a fixed pivot, a crosshead adjustable in the guides and carrying 40 a link-bearer, a link-holder mounted movably in the link-bearer, a shifting link pivoted on the link-holder and having a movable link-block, a valve-stem having operative connection with the link-block, eccentrics 45 having rods connected to the shifting link, a tumbler having a bearing in connection with the fixed pivot and provided with an adjustable bearing cap on the pivot, the tumbler having also two separate wrist-pins, a wrist- 50 pin secured to the crosshead, a lifting link having bearings provided with adjustable caps connected to the wrist-pin of the crosshead and also to one of the wrist-pins of the tumbler, a reach-rod connected to the other 55 one of the wrist-pins of the tumbler, and means for holding or moving the reach-rod.

In testimony whereof, I affix my signature in presence of two witnesses.

ARCHIE L. DORSEY.
